UNITED STATES PATENT OFFICE

151,966

DESIGN FOR A CAMERA BOOM

André Crot, Topanga, Calif., assignor to Motion Picture Research Council, Inc., Hollywood, Calif., a corporation of California

Application July 19, 1948, Serial No. 147,655

Term of patent 14 years

(Cl. D61—1)

To all whom it may concern:

Be it known that I, André Crot, a citizen of the United States, residing in Topanga, in the county of Los Angeles and State of California, have invented a new, original, and ornamental Design for a Camera Boom, of which the following is a specification, reference being had to the accompanying drawings, forming part thereof.

Fig. 1 is a side perspective view of a camera boom, showing my new design;

Fig. 2 is a side perspective view of the opposite side thereof with the parts in different positions of adjustment; and

Fig. 3 is the top plan view thereof.

I claim:

The ornamental design for a camera boom, as shown.

ANDRÉ CROT.
